UNITED STATES PATENT OFFICE.

EDWARD C. CARTER, OF EVANSTON, ILLINOIS.

ANGLE-BAR.

1,155,793.

Specification of Letters Patent.

Patented Oct. 5, 1915.

Application filed February 26, 1915. Serial No. 10,861.

To all whom it may concern:

Be it known that I, EDWARD C. CARTER, a citizen of the United States, residing at Evanston, in the county of Cook and State 5 of Illinois, have invented certain new and useful Improvements in Angle-Bars, of which the following is a specification.

This invention relates to improvements in angle bars adapted for use in forming the 10 joints of railway rails.

The angle bars now commonly employed for the purpose of joining the rails and supporting the same at the joints are of such form that as the mutual wear takes place on 15 coacting wedging surfaces of the angle bar and rail, shoulders are formed which prevent further effective adjustment of the angle bar relatively to the rail.

One object of this invention is to provide 20 an angle bar with a wedging surface which will substantially overcome the above difficulty, and thereby prolong the life of the angle bar.

Another object is to provide an angle bar 25 with wedging surfaces adapted to coact with the lower surface of the rail head and with the upper surface of the rail base, in such a manner that as the wear takes place on the wedging surfaces of the rail and angle bar, 30 and the angle bar is adjusted relatively to the rail, the formation of shoulders—which would prevent further effective adjustment of the angle bar with respect to the rail—will be very materially deferred.

These and other objects of the invention 35 will be more particularly set forth in the following specification, taken in connection with the accompanying drawings, in which I have illustrated one embodiment of the 40 invention.

In the drawings—Figure 1 is a sectional view of a railway rail and angle bar constructed according to present practice, showing the initial contacting surfaces of 45 the rail and angle bar, and, by dotted lines, the ultimate wearing surfaces of the rail after wear has taken place and shoulders have been formed thereon. Fig. 2 is an enlargement of a portion of Fig. 1, showing 50 the upper wedging surfaces. Fig. 3 is a sectional view of the lower portion of the angle bar illustrated in Fig. 1, showing, by dotted lines, the ultimate wearing surface on the lower part of the angle bar and the shoulder formed thereon. Fig. 4 is a sectional 55

view, similar to Fig. 1, but showing an angle bar constructed according to my invention, in the position relative to the rail which it occupies in the initial assemblage. Fig. 5 is an enlargement of a portion of Fig. 4, showing the upper wedging surfaces. Fig. 6 is a view similar to that of Fig. 5, showing a later position of the angle bar relatively to the rail after some wear has taken place. Fig. 7 is a view similar to those of Figs. 5 and 6, showing the relative positions of the angle bar and rail after the wear of the wedging surfaces and the inward movement of the angle bar relative to the rail has been such as to bring the entire upper wedging surface of the angle bar in contact with the under side of the head of the rail. Fig. 8 is an enlarged diagrammatic view representing the theoretical manner in which the wear occurs on the coacting 75 surfaces; and Fig. 9 is a diagrammatic view on an enlarged distorted scale, showing the differential successive positions of various points on the wedging surfaces as wear occurs and the angle bar is advanced toward 80 the rail by tightening the bolts.

Like numerals refer to like parts and elements in the several figures of the drawings.

Referring to Fig. 1 of the drawings, the rail 10 is shown as comprising a head 10^a and a base 10^b, between which the angle bars 11 are adapted to wedge. The angle bar is secured to the rail by a bolt 12 and nut 13, which may be adjusted to regulate the position of the angle bar relatively to the rail, in order to take up the wear on the coacting wedging surfaces of the angle bar and rail and maintain a close wedging fit between the rail and angle bar, so that the angle bars will effectively support the rails at the 95 joint. A plurality of bolts and nuts are of course employed for this purpose, although only one of each appears in the drawing. The upper wedging surface 14 of the angle bar is adapted to coact with the lower wedging surface 15 of the rail head, and when the ordinary angle bar is first assembled on the rail said surfaces are in contact from the outer side of the angle bar, represented by the point 16, to the inner boundary of the upper wedging surface, represented by the point 17. The lower wedging surface 18 of the angle bar is adapted to coact with the upper wedging surface 19 of the rail base, and said wedging surfaces are in contact, 110

in the initial assemblage, from the outer boundary of the wedging surface 19, represented by the point 20, to the inner boundary of the wedging surface 18, represented by the point 21. As the mutual wear of the wedging surfaces of the angle bar and rail takes place, and the bolts which hold the angle bar in position for making it effective as a supporting joint are tightened, the 5 wedging surfaces 15 and 19 of the rail ultimately assume the positions shown by the dotted lines 22 and 23, and shoulders are formed at the points 24 and 25 on the wedging surfaces of the rail, which shoulders 10 substantially prevent any further inward movement of the angle bars with respect to the rail. At the same time the lower wedging surface of the angle bar assumes the ultimate position shown by the dotted line 15 26, and a shoulder 27 is formed on the angle bar, which also prevents further inward movement of the angle bar relatively to the rail. From the time that the shoulders are formed on the wedging surfaces of the rail 20 and angle bar, the mutual wear between the contact surfaces of the rail and angle bar can no longer be compensated for by drawing the angle bar closer to the web of the rail, and in a short time this mutual wear 25 becomes such as to leave the adjoining rails without the necessary support which the angle bars are furnished to provide, and excessive relative deflection of the rails results, with consequent rapid wear of the 30 wheel-bearing surfaces of the rails in the neighborhood of the joint, and of the contact surfaces of the rails and angle bars, thereby decreasing the life of the rails, making a rough track, and increasing the cost 35 of maintenance of the track.

By my invention I substantially overcome the difficulties above described in connection with the present form of angle bar, and defer the formation of a shoulder at the 40 point 24 by providing an angle bar 30 having an upper wedging surface of such contour that when the angle bar is first assembled on the rail, said surface will contact with the lower surface of the rail head only 45 between the boundaries represented by the points 31 and 32, while said surface on the angle bar will diverge from the lower surface of the rail head inwardly of the point 32, as indicated by the divergence of the 50 lines 33 and 34, the divergence being such as to prevent the formation of a shoulder as the angle bar is adjusted inwardly. It will be seen that the upper wedging surface of the angle bar comprises a surface 35 which 55 is initially in contact with and which is angularly disposed with respect to the divergent surface 36, and I also prefer to provide another surface 37, which, in the initial assemblage, projects beyond the adjacent vertical face of the rail head, prefer-

ably inclined downwardly with respect to the plane of the surface 35. I defer the formation of a shoulder at the point 25 by providing the lower part of the angle part 30 with a surface which, in the initial assemblage, coacts with the upper wedging surface of the rail base only between the boundaries represented by the points 38 and 39, and which diverges from said wedging surface of the rail base inwardly of the point 39, as represented by the divergence of the lines 40 and 41. I also provide the lower portion of the angle bar with a horizontally extending surface 42, which projects outwardly from the point 38 in a manner to prevent the formation of a shoulder on the angle bar, as said angle bar is adjusted inwardly toward the rail.

The operation and effect of my improved angle bar will be described in connection with the upper wedging surfaces only. In Fig. 6 I have represented, by dotted lines, the initial position of the angle bar shown in Fig. 5, and, by full lines, a later position of the angle bar after some wear has occurred. In this position the upper wedging surface of the angle bar contacts with the lower wedging surface of the rail head between the boundaries 31 and 43, the area of contact of the wedging surfaces having increased, owing to the wear which has taken place. It will be seen that in this position the inner portion of the wedging surface of the angle bar diverges from the under side of the rail head in the same manner as indicated in Fig. 5. In Fig. 7 I have shown the angle bar in a still later position with respect to the rail, after the bolts have been further tightened and the mutual wear of the wedging surfaces has increased to such a degree that substantially the entire upper wedging surface of the angle bar contacts with the lower surface of the rail head.

Fig. 8 represents diagrammatically the manner in which the wear occurs on the upper wedging surface of the angle bar and the lower wedging surface of the rail head. In the initial assemblage, the upper wedging surface of the angle bar contacts with the under surface of the rail head on the surface 31—32, as previously indicated, while the portion 36 of the wedging surface diverges from the under surface of the rail head, as represented by the divergence of the lines 33 and 34. As the bolts are tightened, and the angle bar is moved toward the rail to take up the wear which has taken place on the wedging surfaces, the newly adjusted position of the upper outer face 30^a of the angle bar may be represented by the dotted line 30^b. As the angle bar moves from the position represented by the line 30^a to the position represented by the line 30^b, the point 31 on the angle bar, representing the outer boundary of the contacting surfaces in the

initial assemblage, will move horizontally inward to the point 44, assuming that all of the wear takes place on the under surface of the rail head. On the other hand, if it be assumed that all of the wear takes place on the angle bar, the point 31 on the angle bar will move to the point 45. In practice the point 31 will move to some intermediate position, as designated by the point 46, and 5 the area of contact of the wedging surfaces will have increased, owing to the wear which has taken place, so that in the position represented by the line 30^b, the area of actual contact of the wedging surfaces may be represented by the line 46—47. Inwardly of 10 the point 47, the upper wedging surface of the angle bar will diverge from the lower surface of the rail head at the same angle as in the initial assemblage. It will be seen 15 that the plane of the contacting surfaces 46—47 in this position lies at an angle to the plane of the original contacting surfaces 31—32, and between the planes represented by the lines 33 and 34. As the wear continues, and the bolts which hold the angle bars to the rails are further tightened, and the angle bar is drawn in to a further extent 20 toward the web of the rail, the area of the wedging surfaces in actual contact will increase without the formation of a shoulder, so that ultimately substantially the entire 25 upper wedging surface of the angle bar will be in contact with the under side of the rail head, as shown in Fig. 7. In order that the area of the surfaces in actual contact may 30 increase outwardly from the rail, as well as inwardly toward the rail, as mutual wear occurs and the angle bar moves inwardly, I have provided the angle bar with the outwardly extending part having the upper 35 surface 37, above described. The effect of this added improvement is to provide a relatively larger area of wearing contact for each position of the angle bar, from that 40 shown in Fig. 5 to that shown in Fig. 7, than would exist if the surface 37 were absent, thereby distributing the wear over larger surfaces and increasing the period required for the entire upper wedging surface 45 of the angle bar to come in contact with the under side of the rail head.

For the purpose of illustrating the successive positions of the wearing surfaces, I have shown in Fig. 9, on an enlarged scale, 50 a diagrammatic representation of the differential successive positions occupied by different points of the wearing surfaces as the angle bar is adjusted toward the rail. In this figure the original lower wedging 55 surface of the rail head is represented by the line 31—50, and the line *a*—*b*—*c*—*d*—*e*—*f*—*g* represents the initial upper wedging surface of the angle bar. The line *b*—*c* represents diagrammatically the initial area 60 of contact of the wedging surfaces, corre-

sponding to the line 31—32 in Figs. 4 and 5; the line *a*—*b* represents the surface 37; and the line *c*—*g* represents the inner diverging surface 36 of the angle bar, which in initial assemblage diverges from the adjacent surface of the rail head, as indicated by the divergence of the lines 33 and 34. Assuming that the bolts have been tightened to move the angle bar inwardly toward the rail a distance *A*—*A'*, the point *a* will move 70 horizontally inward to occupy the position *a'*, which is coincident with the position previously occupied by the point *b* on the angle bar, and at the same time the point *b* will move horizontally inward an equal distance, provided all of the wear takes place in the rail. If it be assumed that the wear takes place equally in the rail and angle bar, the point *b* will move to the point *b'* midway 75 in a vertical plane between the horizontal projection 51 of the original position of the point *b* and the adjacent vertical projection of the point 51 on the lower surface of the rail head. In a similar manner, the point *c* on the angle bar will move inwardly 80 to a point *c'*, which is midway in a vertical plane between the horizontal inward projection of the original position of the point *c* and the adjacent point 46 on the original wedging surface 31—50. In a similar manner 85 it may be determined that the point *d* on the line *c*—*g* moves to *d'*, while the points *e*, *f*, and *g* move to the positions *e'*, *f'*, and *g'*, respectively. The upper wedging surface 90 of the angle bar will then be in contact with the under side of the rail head over the surface represented by the line *a'*—*b'*—*c'*—*d'*, while said surface will diverge from the under side of the rail head, as represented by the line *d'*—*g'*, which line is parallel to the 95 line *c*—*g*. In the same manner it may be determined that after further wear has taken place and the angle bar has been further adjusted toward the rail a distance 100 *A'*—*A''*, the upper surface of the angle bar 105 will contact with the under side of the rail head as represented by the line *a''*—*b''*—*c''*—*d''*—*e''*, and will diverge therefrom, as represented by the line *e''*—*g''*. After the angle bar has moved a still farther distance 110 *A''*—*A'''*, it will contact with the rail head over the surface represented by the line *a'''*—*b'''*—*c'''*—*d'''*—*e'''*—*f'''*, and will diverge therefrom, as represented by the line *f'''*—*g'''*. It will be apparent that the 115 area of actual contact of the wedging surfaces constantly increases as the wear increases and the angle bar is adjusted inwardly, and that in each position the inner portion of the upper wedging surface of the angle bar diverges from the adjacent under surface of the rail head in such a manner as to prevent the formation of a shoulder which would prevent further effective adjustment of the angle bar relatively to the 120 125 130

rail, all of which will be well understood by those skilled in the art.

From a study of the foregoing description, taken in connection with Fig. 9, it will be seen that by varying the initial areas of contact of the wedging surfaces or the angular relation of the different portions 35, 36, and 37 thereof, the succeeding surfaces of contact may be made to vary in any desired manner within a considerable range, so as to secure at all times a tight wedging fit while maintaining a divergence between the inner portion of the wedging surface of the angle bar and the adjacent wedging surface of the rail, in order to prevent or defer the formation of shoulders.

Although I have particularly described the operation and effect of my improved angle bar in connection with the upper wedging surfaces thereof, it will be understood that the operation of the lower wedging surface is similar and effects a similar advantageous result.

During the period elapsing between the application of my improved angle bar to the rail and the time at which the mutual wear has resulted in bringing the entire wedging surface of the angle bar in contact with the adjacent wedging surface of the rail, as represented in Fig. 7, there has been no formation of shoulders on the contact surfaces of the rail, or angle bar, to prevent further tightening of the joint; and it will therefore be seen that my invention has increased the effective life of the angle bar an amount measured by the time required for the angle bar and rail to wear off to such an extent as to contact with each other over the entire wedging surface of the angle bar.

While I have shown and described a particular embodiment of my invention, and have explained the operation and effect thereof in a particular manner for purposes of illustration, it will be understood that I contemplate changes in form and arrangement of parts as necessity may require, or circumstances suggest, and that I do not wish to be limited to the form herein illustrated, or to the mode of operation thereof set forth, except as defined by the appended claims.

I claim:

1. In a device of the class described, a railway rail, an element adapted to be secured to said rail, and means for adjusting said element relatively to said rail, said rail and said element having wedging surfaces which contact over a portion of their areas and thence diverge in the general direction of movement of said element as it is adjusted relatively to said rail.

2. In a device of the class described, a railway rail, a supporting element adapted to wedge between the head and the base of said rail, and means to adjust said element

relatively to said rail, said rail and said element having wedging surfaces which contact over portions of their areas and thence diverge toward the web of said rail.

3. In a device of the class described, a railway rail, a supporting element adapted to be secured to said rail, and means for adjusting said element relatively to said rail, said element having a wedging surface which contacts with said rail over a portion of its area and thence diverges from the plane of said contacting surface inwardly toward said rail.

4. In a device of the class described, a railway rail, a supporting element adapted to be secured to said rail, and means for adjusting said element relatively to said rail, said element having a wedging surface which contacts with said rail over a portion of its area and thence diverges from the plane of said contacting surface toward said rail from one side of said contacting surface and away from said rail from the other side of said contacting surface.

5. In a device of the class described, a railway rail, an angle bar adapted to wedge between the head and base of said rail to support the same at a joint, and means for adjusting said angle bar relatively to said rail, said angle bar having upper and lower wedging surfaces adapted to engage the lower surface of the rail head and the upper surface of the rail base respectively, said wedging surfaces being arranged to contact with said rail over portions of their areas and to diverge from the planes of said contacting surfaces inwardly toward said rail.

6. An angle bar adapted to be adjustably secured to a railway rail, said angle bar having a wedging surface arranged to contact with a surface of said rail over a portion of its area and thence to diverge from said surface of said rail in the general direction of movement of said angle bar as it is adjusted toward said rail.

7. An angle bar adapted to be secured to a railway rail, said angle bar having an upper wedging surface arranged to contact over a portion of its area with the under surface of the head of said rail and thence to diverge from the plane of said contacting surfaces toward the web of said rail.

8. An angle bar adapted to be secured to a railway rail, said angle bar having a lower wedging surface arranged to contact over a portion of its area with the upper surface of the base of said rail and thence to diverge from the plane of said contacting surfaces inwardly toward the web of said rail.

9. An angle bar adapted to wedge between the head and the base of a railway rail, said angle bar having a wedging surface which is arranged to contact with the adjacent wedging surface of said rail over a longitudinally extending portion of its area and

thence to diverge angularly from the plane of contact transversely of and toward the web of said rail.

10. An angle bar adapted to be adjustably secured to the web of a railway rail, said angle bar having an upper wedging surface which is adapted to contact with the under wedging surface of the head of said rail over a portion of its area and thence to diverge from said undersurface of the head inwardly toward the web of said rail, whereby as wear occurs and the angle bar is adjusted toward said rail the formation of a shoulder on the rail will be prevented.
15. 11. An angle bar adapted to be adjustably secured to a railway rail, said angle bar having an upper wedging surface which is adapted to contact over a portion of its area with the under wedging surface of the rail head and thence to diverge from the surface of contact inwardly toward the rail and outwardly away from the rail, whereby as wear occurs and said angle bar is adjusted toward the rail the area of contact of the wedging surface of the angle bar increases inwardly toward the rail and outwardly away from the rail.
20. 12. An angle bar adapted to be adjustably

secured to a railway rail to support the same at a joint, said angle bar having a lower wedging surface which is adapted to contact over a portion of its area with a longitudinally extending portion of the upper surface of the base of said rail and thence to diverge from said surface of the rail inwardly toward said rail, whereby as wear occurs and the angle bar is adjusted toward the rail the formation of a shoulder on said rail is prevented.

25. 13. An angle bar adapted to be adjustably secured to a railway rail, said angle bar having a lower part adapted to engage the base of said rail and to extend outwardly beyond the edge of said base, said part having a lower wedging surface adapted to contact with a portion of the upper surface of the base from the outer edge of said base inwardly and to diverge upwardly from the surface of contact outwardly of the edge of said base.

In testimony whereof, I have subscribed my name.

EDWARD C. CARTER.
